(57) **CLAIM**

(21) Appl. No.: **29/352,451**

The ornamental design for a cell phone charging station, as shown and described.

(22) Filed: **Dec. 21, 2009**

DESCRIPTION

(51) **LOC (9) Cl.** **13-02**

FIG. 1 is a perspective view of the present invention cell phone charging station;

(52) **U.S. Cl.** **D13/108**

FIG. 2 is a front elevational view of the cell phone charging station;

(58) **Field of Classification Search** D13/107–110,
D13/118–119, 184, 199; D14/251, 253,
D14/432, 434; 320/107–115

FIG. 3 is a rear elevational view of the cell phone charging station;

See application file for complete search history.

FIG. 4 is a right side elevational view of the cell phone charging station;

(56) **References Cited**

FIG. 5 is a top plan view of the cell phone charging station; and,

U.S. PATENT DOCUMENTS

FIG. 6 is a bottom plan view of the cell phone charging station.
